UNITED STATES PATENT OFFICE.

ROBERT F. DOLL, OF CHICAGO, AND JOHN C. THIES, OF BARRINGTON, ILLINOIS.

FOLDING CRATE.

1,426,363.

Specification of Letters Patent. Patented Aug. 22, 1922.

Application filed July 2, 1920. Serial No. 393,648.

To all whom it may concern:

Be it known that we, ROBERT F. DOLL and JOHN C. THIES, citizens of the United States, residing at Chicago and Barrington, 5 county of Cook, State of Illinois, respectively, have invented certain new and useful Improvements in Folding Crates, of which the following is a specification.

This invention relates to improvements in 10 folding crates.

An important object of the invention is the provision of a folding crate which can be simply and rigidly maintained in an upright position, and which can be compactly 15 folded to occupy a relatively smaller space than when in an upright position.

A further object of the invention is the provision of a folding crate which involves a minimum of parts yet effectively and completely meeting all the requirements of a 20 folding crate for shipping merchandise and the like.

A further object of the invention is the provision of a folding poultry crate embodying 25 the means for access to the interior of the crate without liability of escape of the poultry therefrom.

Other objects and advantages will be apparent during the course of the following detailed description.

In the accompanying drawings forming a part of this specification and in which like characters designate like parts throughout the same,

25 Figure 1 is a perspective view of the folding crate.

Figure 2 is a perspective view of the folding crate in a collapsed condition.

Figure 3 is a cross sectional view showing 40 the folding crate when in an upright position.

Figure 4 is a cross sectional view showing the folding crate with the sides about to be folded,

45 Figure 5 is a cross sectional view showing the folding crate when in a folded condition.

Figure 6 is a fragmentary cross sectional view showing the means for locking the crate in an upright position.

50 Figure 7 is a fragmentary cross sectional view of a corner of the folding crate.

Figure 8 is a fragmentary cross sectional view taken through the top section of the crate.

55 In the drawings, wherein for the purpose

of illustration is shown a preferred embodiment of my invention, the letter A designates the platform structure of my invention having side sections B and end sections C hingedly mounted thereto, top sections D 60 being preferably hinged to the side sections B.

The platform structure A is preferably composed of imperforate material having projections extending outwardly of the sides 65 and end sections of the crate as is clearly shown in Figure 1 of the drawings.

Base boards 10 are mounted upon the platform structure and rigidly connected thereto by a strip 11, the base boards 10 in reality 70 forming the bottom portion of the end sections C. A strip 12 is provided transversely across the floor of the platform structure A for securely bracing said platform structure.

75 It is preferred that the sides, ends and top sections be formed of slats 13, the slats 13 of the side sections B being transversely reinforced along their edges by braces 14 and the end sections C being transversely reinforced along their outer edges by braces 15.

80 Additional transverse braces 16 are provided upon the sides B and intermediate the ends thereof and braces 17 are provided upon the end sections B and intermediate the ends 85 thereof.

85 The braces 14 and 15 are substantially triangular in shape and adapted to form a corner post of substantially rectangular formation when the crate is in an upright position and in such manner that their abutting faces cooperate to rigidly brace the structure. The side sections B are foldably mounted upon the platform structure A by hinges 18 and adapted to fold inwardly 90 upon the platform structure A.

95 Top sections D are foldably connected to the side sections B by hinges 19 and foldable outwardly thereon from an upright position and in such manner that when the sides B 100 are folded the respective top D will be immediately on top as is shown in Figure 2 of the drawings.

105 Braces 15 are preferably formed of two sections each, a section 20 being rigidly connected to the base board 10 and a section 21 foldable within the end section C and attached thereto. Hinges 22 are provided to connect the sections 20 and 21 of each of the braces 15 to permit the end sections C to 110

be readily folded over the top and side sections as is clearly shown in Figure 2 of the drawings.

Lock blocks 23 are provided upon the inside of end sections C being preferably mounted upon the bracing pieces 17, apertures 24 are provided therein for the reception of a locking rod 25 preferably constructed of bar metal. Additional lock blocks 26 are provided upon the upper side of top section 27 having apertures 28 therein likewise adapted for the reception of the locking bar 25, when the folding crate is in an upright position. Apertures 29 are provided in the lock block 23 at substantially right angles to apertures 24 and adapted for the reception of the locking bar 25 to maintain the crate in collapsed position when the crate is folded.

20 In the case of a poultry crate, it may be desired to handle poultry without the liability of their escape from the crate and to facilitate this straps 30 are nailed or otherwise secured on the cross sections of the crate in such a manner as to permit removal of slats 31 and 32 therefrom. It will also be observed that a section of the top 33 can be swung outwardly when the rest of the crate is locked in an upright position for easy removal of contents from the folding crate. This section of the folding top is provided with sliding locking arms 34 and 35 slideable within a lock 36 and adapted to engage the under surface of the top section 27 for locking top section 33 in place when the crate is in an upright position.

In operation, the sides C are first collapsed upon the platform structure A and the top D folded upon their respective sides 40 B. The end sections C are then folded or collapsed upon the top sections D, and the locking rods 25 inserted through apertures 29 and apertures 37 in base boards 10 for securely locking the folding crate in a collapsed condition.

It is to be understood that the form of our invention herewith shown and described is to be taken as a preferred example of the same and that various changes in the shape, 50 size and arrangement of parts may be re-

sorted to without departing from the spirit of the invention or the scope of the subjoined claims.

We claim:

1. In a folding crate, the combination of 55 a platform structure, foldable sides, ends, and a pair of top sections for said foldable crate, a rod for locking the sides, ends and one of the top sections in an upright position, and a second locking means for the 60 other of the top sections, whereby the latter can be separately used to secure ingress into the crate.

2. In a folding crate, the combination of 65 a platform structure, foldable ends, sides, and top sections, lock blocks mounted upon said end sections having apertures therein, and a locking rod adapted for insertion through the apertures of said lock blocks to lock the crate in an upright or folded position.

3. In a crate, the combination of a platform, end and side sections, a pair of hinged top sections for said crate, lock blocks carried by said end sections and having aligned 75 apertures therein, lock members carried by a hinged top section and having apertures therein aligned with the apertures of the above mentioned lock blocks, a locking bar adapted for insertion through said apertures to hold the crate and a hinged top section in rigid relation, and separate locking means for the other of the hinged top sections.

4. In a folding crate, the combination of 85 a platform structure, foldable sides hinged to said platform structure, top sections hingedly connected to said side sections and foldable thereon, foldable ends for said crate, said sides and top sections adapted to 90 be folded on said platform structure in such position that one side and its respective top, is out of overlapping relation with respect to the other side and its respective top, and said end section adapted for positioning 95 upon said side and top sections in folded position.

ROBERT F. DOLL.
JOHN C. THIES.
